UNITED STATES PATENT OFFICE.

ARTHUR WARNER, OF PHILADELPHIA, PENNSYLVANIA.

CONVEYER.

Application filed December 11, 1923. Serial No. 679,891.

To all whom it may concern:

Be it known that I, ARTHUR WARNER, a citizen of the United States, residing at Philadelphia, in the county of Philadelphia and State of Pennsylvania, have invented certain new and useful Improvements in Conveyers, of which the following is a specification.

My invention relates to conveyers and more particularly to the type known as the belt conveyers. The objects are to provide a conveyer which will do away with the ordinary belt troughing rollers, the return belt rollers and the supporting structures and bridges therefor; which will be shaped so as to take the greatest load with the least strain; which will have no parts touching the carrier to wear the same; which will require less power for its operation; which will be lighter and cheaper to manufacture and install than conveyers heretofore made, and which is adapted to carry material up a greater inclination than heretofore possible with this type of conveyers.

These objects, and other advantageous ends which will be described hereinafter, I attain in the following manner, reference being had to the accompanying drawings in which—

Figure 1 is a side elevation partly in section of a conveyer constructed in accordance with my invention.

Figure 2 is an enlarged section on line 2—2 of Figure 1.

Figure 3 a view similar to Figure 2 showing a modified form of conveyer supporting means,

Figure 4 a fragmentary plan view of the conveyer shown in Figure 1,

Figure 5 a modified form of supporting and attaching means for the carrier,

Figure 6 a section on line 6—6 of Figure 5,

Figure 7 a fragmentary plan view of another form of conveyer,

Figure 8 a section on line 8—8 of Figure 7,

Figure 9 a modified form of the conveyer shown in Figure 1 showing it as used for carrying material up a steep incline,

Figure 10 a section on line 10—10 of Figure 9, and

Figure 11 a central section through a modified form used for long conveyers.

In the drawings, for clearness of illustration, I have shown cables supporting a car-

rier belt but any suitable chains and carrier may be substituted for the cables and belt.

Referring to the drawings, 1 indicates my improved conveyer, 2 the take-up supporting means, 3 the driving supporting means, 4 the means for feeding material to the conveyer and 5 the means for receiving material from the conveyer. The take-up supporting means may be of any suitable construction which includes wheel 6 adjustably mounted in a slotted frame 7 and held in adjusted position by means of screw mechanism shown at 8. The driving means may be of any suitable construction which includes wheels 70 9 connected with a train of gearing 10 connected to a motor 11. The feeding means may be of the usual type which includes a hopper 12, a reciprocating truck 13 mounted under the hopper to feed material 14 onto the conveyer. The material receiving means 5 may be of any suitable construction which includes a hopper 15 for guiding material to a receptacle or bunker 16 or any other desired place.

My improved conveyer 1 consists of endless cables 17 mounted on the wheels 6 and 9 and having suspended therebetween an endless carrier or belt 18. The means for suspending the carrier from the cables consist of clips 19 having one end 20 hinged to belt 18 as shown at 21, and the other end 22 wrapped around the cable and secured thereto in any suitable manner. The clips 19 are preferably made from spring metal so that 90 a resilient suspension means for the belt is provided.

Figures 5 and 6 show modified means for suspending the belt from the cables, consisting of clips 19^a having one end 22^a clamped to the cables and the other end 20^a hinged at 21^a to one end of a strap 23. The other end of the strap extends to the other cable and is connected thereto in a similar manner. The belt 18 may be riveted to the strap at 24 or otherwise secured thereto. These straps remove the strain from the edge of the belt and thereby allow a belt or lighter weight to be used.

In Figure 3 I have shown the wheels 6^a and 9^a disposed at an incline to each other so that the distance between the upper runs of the cables will be less than the distance between the lower runs. This position of the wheels causes the lower run of the belt 18 to stretch and extend beyond the side edges of the upper run, as shown at 25, so

that any material falling from the upper run will be caught by the lower run and brought adjacent the feeding means where it may be again fed onto the upper run.

5 In Figures 7 and 8 I have shown a chain 17^a connected to a carrier 18^a by a hinge 26. In Figures 9 and 10 I have shown the conveyer 1 arranged for carrying material up a steep incline, by placing partitions 27 10 within belt 18 and securing them thereto in any suitable manner, such as by securing their lower edges as shown at 28, and by hooking their upper edges 29 to a rod 30 secured to the belt. This arrangement may 15 be substituted for the bucket type of conveyer used for steep inclines and has the advantage of being capable of passing through what is known as a traveling tripper which is movable along the conveyer for receiving the discharged material from any 20 part of the conveyer and delivering it to various parts of a bunker.

Figure 11 shows a strut 31 connected to the hinges 22 for keeping the edges of the belt separated. The number of these struts necessary in a conveyer depends on the length of the conveyer and the material conveyed.

In use, as the material is discharged from 30 the feeding means 4 onto belt 18, the weight of the material will cause the belt to take substantially the curve shown at 32 in Figure 2 which is similar to a catenary curve. The belt being so curved is capable of carrying 35 the greatest load with the least strain. As the upper run of the conveyer is moved upward by the driving means 3, cables 17 support belt 18 by the clips 19. This does away with the usual rollers for troughing 40 or shaping the curvature of the belt and the rollers for supporting the lower or return run of the belt. As the conveyer passes over wheels 9 of the driving means, the material is discharged into the receiving means 5. 45 The belt in its lower run will take the curvature shown at 33 in Figure 2. The hinge connections 22 allow the belt to take this natural shape without in any way straining the same. As the conveyer passes over the 50 wheels 6 of the take-up means 2, the hinge connections 22 allow the belt to swing from the position shown at 33 and take the shape shown at 32. The belt is thus always ready to receive material from the feeding means 55 4. Any vibrations produced on the belt during its operation are absorbed by the spring clips 19.

When the wheels 6^a and 9^a of the take-up and driving means 2 and 3 are disposed at 60 an incline to each other as shown in Figure 3, the upper run of the belt as it passes over the wheels 9^a is stretched so that the side edges extend beyond the side edges of the top run as shown at 25.

By constructing a conveyer as above set 65 forth it may be manufactured and installed at a very low cost and the repairs and upkeep are reduced to a minimum.

While I have described my invention as taking a particular form, it will be understood that the various parts may be changed without departing from the spirit thereof, and hence I do not limit myself to the precise construction set forth, but consider that I am at liberty to make such changes and 75 alterations as fairly come within the scope of the appended claims.

Having thus described my invention, what I claim as new and desire to secure by Letters Patent is:—

1. A conveyer including cables; resilient means attached to the cables, and a carrier suspended from the resilient means.

2. A conveyer including cables; spring clips attached to the cables, and a carrier 85 suspended from the clips.

3. A conveyer including cables; spring strips having one end attached to the cables, and an endless carrier attached to and suspended from the other end of the strips. 90

4. A conveyer including cables; spring strips having one end attached to the cables, and an endless carrier hinged to and suspended from the other end of the strips.

5. A conveyer including cables; spring strips having one end wrapped around to embrace the cables, and an endless carrier attached to the other end of the spring strips. 95

6. A conveyer including cables; a carrier; 100 straps secured to the carrier, and resilient means connected with the straps and the cable.

7. A conveyer including cables; spring clips attached to and embracing the cables; 105 straps hinged to the clips; a belt secured to the straps, and means for moving the cables.

8. A conveyer including cables; a belt; suspending means on the cables attached adjacent the edge of the belt; partitions secured to the belt between and near its edges, and means for moving the cables. 110

9. A conveyer including cables; a belt; spring strips secured to the cables and attached to the belt; partitions secured to the 115 belt, and means for moving the cables.

10. A conveyer including cables; a partitioned carrier spaced from the cables; suspending means secured to the cable and attached to the carrier, and means for moving 120 the cables.

In testimony whereof I have signed my name to this specification in the presence of two subscribing witnesses.

ARTHUR WARNER.
